PROTECTIVE SYSTEM

Raymond C. Samuels, Philadelphia, Pa., assignor
to General Electric Company, a corporation of
New York

Application October 13, 1932, Serial No. 637,624

5 Claims. (Cl. 175—294)

My invention relates to control systems, more particularly to a protective relay arranged to prevent a contactor from repeatedly opening and closing in case its holding resistor should be open circuited, and has for an object the provision of a simple and reliable system of this character.

In the operation of automatic substations or other equipment which is to be remotely controlled, it is desirable to prevent the operation of the circuit controlling switch in case its holding resistor should become open circuited. Heretofore the result of an open circuit in the holding resistor caused a pumping action of the switch. That is to say, the operating circuit of the switch would be completed, the switch would close, and by means of interlock contacts the operating circuit would be interrupted and a circuit would be completed through the holding resistor. But because of the open circuit in the holding resistor the contactor would immediately open. This cycle of operations might continue until the operating coil of the switch burned out.

In carrying out my invention in one form thereof, I provide connections whereby the operation of the circuit controlling switch is dependent upon the completion of a circuit through the holding resistor. More particularly, I provide a relay with its operating coil in series with the holding resistor and with its contacts arranged to complete the operating circuit to the switch so that the operating circuit cannot be completed upon the failure of the resistor.

For a more complete understanding of my invention reference should now be had to the accompanying drawing in which I have illustrated diagrammatically my invention.

Referring now to the drawing, I have shown my invention in one form as applied to a circuit controlling switch 10 provided with the usual armature an operating coil 11 and normally closed interlock contacts 12. A holding resistor 14 is connected in circuit with the operating coil 11. A protective relay 15 has its holding coil 16 connected in series with the holding resistor 14 and the normally closed interlock contacts 12. The contacts 18 of the relay 15 are arranged to short circuit the holding resistor 14.

In explaining the operation of my invention, it will be assumed that the supply lines 20 and 21 are energized from a suitable source of supply (not shown) and that a control switch 22 has been closed. The energizing circuit for the operating coil 16 of the relay 15 depends upon a circuit including the resistor 14. This circuit may be traced from the supply line 20, control

switch 22, conductor 24, holding resistor 14, operating coil 16, interlock contacts 12, and to the other supply line 21. The relay 15 immediately closes its contacts 18 to complete an energizing circuit for the operating coil 11 of the circuit controlling switch 10. This circuit may be traced from the supply line 20, control switch 22, conductors 24 and 26, relay contacts 18, and by conductors 27 and 28, operating coil 11 to the other supply line 21. The circuit controlling switch 10 is immediately operated to close its contacts 30 and to open the normally closed interlock switch contacts 12. The opening of the contacts 12 interrupts the energizing circuit for the relay 15 which immediately operates to open its contacts, thereby inserting the holding resistor 14 in series with the operating coil 11. The holding circuit may be traced from the supply line 20, switch 22, conductor 24, holding resistor 14, conductor 32, operating coil 11 and to the other supply line 21.

By means of the contacts 30 a circuit breaker 34 of the latched-in type is arranged to be closed through the cooperation of the relay 35. The energizing circuit for the relay 35 may be traced from supply line 20, conductor 37, interlock contacts 38 operating with the contactor 34, operating coil 39, relay 35, contacts 30 of the controlling switch 10 and to the other supply line 21. Consequent to the closing of the relay 35 an energizing circuit for the operating coil 40 in contactor 34 may be traced from the supply line 20, conductor 42, operating coil 40, contacts of the relay 35 and by conductor 43 to the other supply line 21.

In order to operate the latched-in contactor 34 to its open position, it is only necessary to open the control switch 22. The result is the deenergization of the operating coil 11 of the circuit controlling switch 10. As the contacts 30 are opened the contacts 45 operated with this switch are closed to complete an energizing circuit for the trip coil 46 of the latched-in contactor. This circuit may be traced from supply line 20, by conductor 48, interlock contacts 49 operated with the contactor 34, trip coil 46, contacts 45 and to the other supply line 21.

Similarly additional contactors (not shown) may be controlled by adding additional contacts 50, shown by broken lines, to the switch 10.

It will now be assumed that a failure of the holding resistor 14 has occurred, or, in other words, that the holding resistor is open circuited. If the control switch 22 is now closed an energizing circuit cannot be completed for the operating coil 16 of the relay 15, because the operation of the

relay 15 depends upon the completion of its energizing circuit through the resistor 14. Consequently, the circuit controlling switch 10 cannot be operated unless the relay 15 is operated to exclude the holding resistor 14 from the operating circuit to the coil 11.

If it were not for the provision of relay 15, the closing of the control switch 22 during the open circuiting of the resistor 14 would cause the switch 10 to close and to open in rapid succession, since contact 18 would be operated by relay 11 instead of by relay 16. This pumping action would cause damage to the switch 10. Furthermore, the pumping action produced by the opening and closing of the contactor 34 would result in heavy "bumps" on the line and might result in considerable damage.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

25 What I claim as new and desire to secure by Letters Patent of the United States, is,—

1. In combination, a switch provided with an operating coil, a holding resistor, connections for connecting said resistor in series with said coil thereby to limit the current flow through said coil to a predetermined value, an operating circuit for increasing the energization of said coil, and means for preventing repeated operation of said switch in case of failure of said resistor comprising a relay having its operating coil connected in series with said resistor, and connections for connecting said relay in said operating circuit so that the completion of said operating circuit depends upon the operation of said relay.

40 2. A control system including a switch provided with an operating coil, a holding resistor, connections for connecting said resistor in series with said operating coil to form a holding circuit for said switch, a relay provided with an operating coil for increasing the energization of said switch operating coil to close said switch, normally closed contacts arranged to be opened when said switch closes, and connections including said resistor and said contacts for controlling the energization of said relay operating coil.

3. In combination, a circuit controlling switch provided with a plurality of contacts one of which is normally closed, an operating coil for said switch, a relay provided with normally open contacts and an operating coil, a current limiting resistor, connections for connecting said resistor in series with said operating coils, connections for connecting said relay contacts across said resistor, connections for including said normally closed contacts in circuit with said relay operating coil, and means including said resistor for controlling the energization of said relay operating coil the said means being ineffective upon failure of said resistor.

4. The combination with a power supply circuit, a normally open switch, a magnet coil for closing said switch and a circuit for said coil connected to said supply circuit, of a resistance in series with said coil sufficient to prevent said magnet coil from closing said switch while a predetermined voltage exists across said supply circuit, and a relay having a coil connected to said supply circuit in series with said resistance, said relay adapted to cut out said resistance when said predetermined voltage exists, to permit said magnet coil to close said switch, a normally closed interlock switch connected in circuit with said relay coil, and means responsive to the closing of said switch for opening said interlock switch whereby said relay operates to re-insert said resistance in series with said magnet coil.

5. The combination with a power supply circuit, a normally open switch provided with an armature, a magnet coil for operating said armature to close said switch and a circuit for said coil connected to said supply circuit, of a resistance in series with said coil sufficient when in series with said coil to prevent said magnet coil from closing said switch while a predetermined voltage exists across said supply circuit, and electroresponsive means connected to said supply circuit in series with said resistance for short circuiting said resistance when said predetermined voltage exists and thereby cause said magnet coil to operate said armature to close said switch, and means responsive to the movement of said armature in closing said switch for operating said electroresponsive means to re-insert said resistance in series with said magnet coil.
